UNITED STATES PATENT OFFICE

CHRISTIAN CHRISTIANSEN, OF FARGO, NORTH DAKOTA

SHOCK-FORMING MACHINE

Application filed August 14, 1931. Serial No. 557,175.

The invention relates to shock-forming machines of the general type shown in my U. S. Patents 1,295,271 of February 25, 1919, 1,413,966 of April 25, 1922, 1,640,598 of August 30, 5 1927 and 1,656,774 of January 17, 1928.

In the prior machines, a rotary table has been mounted upon a portable frame to support the shock while it is being formed and to rotate said shock, a cylindrical receiver has 10 been provided above the table and in axial alignment therewith to retain the shock while it is being formed, and provision has been made for rearwardly shifting the receiver to force a completed shock from the rotary table, 15 said receiver having a rearwardly swingable gate section which opens to allow discharge of the shock. The rotary table has necessarily been located rather close to the ground, with the result that the prior machines would 20 not effectively clear rocks or other obstructions in the field. It has therefore been the principal object of the present invention to improve upon the prior structures by mounting the shock-supporting table and the shock-forming receiver upon a drop frame, which 25 frame is normally raised quite a distance above the ground, but is lowered whenever a shock is to be discharged. Hence, the machine will more readily clear field obstructions and the operator may easily spot an area 30 substantially free from such obstructions upon which to discharge any completed shock.

Another object of the present invention 35 has been to improve upon the means heretofore provided for finishing the crown of the shocks. Previously, a roller disposed substantially radially of the receiver, at the upper end of the latter, has been the sole provision for finishing the shock crowns, but it 40 has been found that when the stems or stalks of the grain are unusually long, difficulty will be encountered in properly crowning the shocks. Such difficulty however is overcome 45 by severing the stems and in order to accomplish this end, I place a continuous knife upon the above-mentioned roller.

With the foregoing in view, the invention 50 resides in the novel subject matter hereinafter described and claimed, description being ac-

complished by reference to the accompanying drawings.

Fig. 1 is a side elevation of a shocking machine improved in accordance with the present invention, showing the drop frame in 55 its normal raised position.

Fig. 2 is a view similar to Fig. 1, but showing the drop frame lowered to shock-discharging position.

Fig. 3 is a vertical transverse sectional view 60 substantially on line 3—3 of Fig. 2.

Fig. 4 is a horizontal sectional view substantially on line 4—4 of Fig. 3.

Fig. 5 is a detail transverse sectional view 65 showing a slight modification hereinafter described.

Fig. 6 is a perspective view of the shock-crowning roller and the continuous knife carried thereby.

Fig. 7 is a transverse sectional view on line 70 7—7 of Fig. 6.

Fig. 8 is a side elevation of the roller and the knife carried thereby.

In the drawings above briefly described, 75 one illustrative construction has been shown and will be rather specifically explained, with the understanding however that within the scope of the invention as claimed, numerous variations may be made.

M denotes a main horizontal frame having 80 ground wheels W and W' at its rear end but intended at its front end (not shown) for connection with a tractor. The wheels W and W' are mounted on the aligned ends 10 and 11 of a cranked axle 12, said ends being turnable in bearings 13 carried by the frame M. This frame, in the present disclosure, embodies two longitudinal bars 14 and 15 disposed at the inner sides of the wheels W' and W, respectively, and a third longitudinal bar 16 disposed at the outer side of the wheel W, the rear ends of said bars carrying the bearings 13. The front portions of these bars 14, 15 and 16 may be rigidly connected with 85 each other in any desired way and I have shown them tied together by transverse members 17 and 18. Rigid, rearwardly projecting arms 19 are shown secured to the member 17 and projecting rearwardly from the latter, and two hangers 20 are pivoted at 21 to the 90 100

down-turned ends 19' of said arms. A horizontal drop frame D under the main frame M, is pivoted at its front end to the lower ends of the hangers 20, as indicated at 22, the rear portion of said drop frame being provided with bearings 23 through which the depressed central portion of the cranked axle 12, passes turnably. The hangers 20 and the crank arm portions 24 of the axle 12 are substantially parallel, and said links and axle may swing to allow raising and lowering of the drop frame D. Normally, this frame D occupies the forward raised position shown in Fig. 1, being held in this position by latch means 25 which is pivoted to said frame D and is engaged by a suitable spring device 26 with an appropriate part of the main frame M. When this latch means 25 is released, for instance, by a pull rod 27, the frame D descends to a rear lowered position as seen in Fig. 2, the rearward movement of said frame being limited by any desired means such as a stop rod 28. Preferably, movement of the frame D to its lowered position, is cushioned by an appropriate shock-absorbing spring 29.

For illustrative purposes, the drop frame D is shown as embodying parallel longitudinal side bars 30 connected at intervals by transverse members 31. Between the side bars 30, is a rotatable shock-supporting table 32, said table having a central bearing 33 and resting near its periphery upon rollers such as 34 and 35 (see Fig. 3). The roller 35 is carried by a shaft 36 rotatable in a bearing 37 on one of the side bars 30, said shaft having a sprocket 38 engaging a sprocket chain 39. This chain also engages another sprocket 40 which rotates bodily with a third sprocket 41, the two sprockets 40 and 41 being carried by a radius link 42 pivoted upon the shaft 36. A driving chain 43 engages the sprocket 41 and a sprocket 44, the latter being loose upon a short transverse shaft 45 which is mounted in appropriate bearings 46 on the bars 15 and 16 of the main frame M. Another radius link 47 is pivoted upon shaft 45 and carries the shaft or the like of the sprockets 40 and 41. Shaft 45 is constantly driven by a chain 48 and sprockets 49—50 from the wheel W which constitutes a bull wheel for the machine. By means of an appropriate clutch 51, the sprocket 44 may be connected with the shaft 45, to drive the chain 43, the sprockets 40 and 41, the chain 39, the sprocket 38, the shaft 36 and the roller 35, for the purpose of rotating the table 32. Such rotation of the table is effected continuously while forming a shock, but is preferably discontinued when forcing a shock from the table. The driving means for the table, it will be observed, is of such nature that it will not interfere with raising and lowering of the drop frame D, attention being here invited

to the differences in the positions of the radius links 42 and 47, in Figs. 1 and 2.

Two rigid vertical side frames 52 are carried by the drop frame D. For illustrative purposes, each of these side frames is shown as embodying a front vertical bar 53, an intermediate relatively tall vertical bar 54, and a rear bar 55, the upper portions of the three bars being secured to a horizontal longitudinal track 56. Rollers 57 engage the lower edges of the two bars 56 and other rollers 58 engage the upper edges of the bars 30, these rollers being mounted on an appropriate framework 59 which carries the main section 60 of a cylindrical receiver R. This receiver is normally over and in axle alinement with the rotary table 32 to co-operate with the latter in forming a shock, and said receiver embodies an upwardly slideable and rearwardly swingable gate section 61 having rollers 62 which engage rearwardly inclined trackways 63. When the receiver is shifted rearwardly, it forces a completed shock from the rotary table 32 and the gate section 61 slides upwardly and swings rearwardly in the same manner as in Patents 1,413,966 and 1,640,598, above mentioned, allowing the receiver to clear the shock. Before the receiver is rearwardly shifted, in the improved machine, the drop frame D carrying said receiver and the table 32, is allowed to lower to the position shown in Fig. 2, placing the shock much nearer the ground so that there is no danger of disrupting it as it is pushed from the table. Lowering of the frame D takes place by gravity in the present disclosure and occurs immediately upon release of the latch means 25, and unique provision is made whereby said drop frame is restored to its raised forward position after the shock has been discharged.

Two unloading chains 64 extend longitudinally of the main frame M and are carried by the latter, said chains being trained around front and rear sprockets 65 and 66, the rear sprockets 66 being rotatably supported by appropriate brackets or the like 67 carried by the bars 14 and 15, while the front sprockets 65 are secured upon short transverse shafts 68 mounted in appropriate bearings 69 secured to said bars 14 and 15. By means of intermeshing spur gears 70, the shafts 68 are operatively connected with a transverse shaft 71 which may be driven by a chain 72 and sprockets, from the shaft 45. The driving sprocket 73 for the chain 72, is loose upon the shaft 45 but may be connected with the latter by an appropriate clutch 74. This clutch and the clutch 51 are of course manually controlled.

Two longitudinal links 75 are pivoted at their front ends to the chains 64 respectively, as shown at 76, the rear ends of said links being pivoted at 77 to the receiver frame 59. These links 75 and chains 64, when the latter

are driven, serve to first rearwardly shift the receiver R to shock-discharging position and to then forwardly return said receiver to its position over the rotary table 32. The chains 64 however are not driven to effect this work, 5 until the drop frame D is lowered as seen in Fig. 2. When this frame descends, the receiver frame 59 pulls to some extent upon the links 75 and the latter cause some idle traveling of the chains 64, as will be seen by comparing Figs. 1 and 2. As soon as the clutch 74 is thrown in however, the sprocket 73 and chain 72 drive the shaft 71, the latter drives the gearing 70, and said gearing drives the sprockets 65, thereby operating the chains 64 and the links 75 to force the receiver R rearwardly to shock-discharge position. As the pivots 76 pass upwardly around the rear guide sprockets 66 of the chains 64, the receiver reaches the limit of its rearward movement, and as said pivots 76 travel forwardly with the upper reaches of the chains 64, the links 75 are pulled to forwardly return the receiver into its proper position above the table 32. This receiver reaches the limit of its forward movement with respect to the frame D, before the chains 64 have disposed the pivots 76 in front of the sprockets 68. It thus follows that as the forward movement of 20 the links 75 is completed, the frame 59 of the receiver thrusts forwardly upon the drop frame D, thereby moving the latter forwardly. As this frame is thus forwardly moved, the hangers 20 and the cranked axle 12 cause it to ascend, and by the time the chains 64 and links 75 have moved the frame D as far as possible, the latch means 25 has come into play to hold said frame D in raised position as seen in Fig. 1. The clutch 74 is then disengaged and the machine is in readiness for the formation of another shock.

While any preferred means may be employed for limiting the forward travel of the receiver R upon the drop frame D, I have shown a stop 78 on one of the bars 30 in the path of one of the rollers 58, for this purpose, and it may be considered that there is a similar stop at the opposite side of the machine.

A corrugated roller 79 is disposed substantially radially at the upper end of the receiver R, the shaft of said roller being pivoted at 50 80 to allow the roller to vertically move when finishing a shock, as in Patent 1,640,598, above mentioned. This roller 79 is driven by gearing 81 from a vertical telescopic shaft 82, this shaft being in turn driven by gearing 83 from another telescopic shaft 84, one end of the latter being driven by a chain 85 and appropriate sprockets from the shaft 45. The chain-driven portion of the shaft 84 is carried by standards or the like 86 secured to suitable parts of the main frame M, and said shaft 84 embodies appropriate universal joints 87 which, together with telescopic action of the shaft, takes place when the receiver moves 55 60 65

rearwardly or forwardly. Other universal joints 88 are provided in the shaft 82 to allow the necessary movement of the latter as the roller 79 swings upwardly upon completion of a shock. A portion of this shaft 82, 70 through the instrumentality of a sprocket chain 89 and sprockets, drives a vertical friction-reducing roller 90 at the wall of the receiver.

Surrounding the roller 79 and projecting 75 laterally from the periphery thereof, is an annular knife 91 whose structure is most clearly shown in Figs. 6 to 8. As a shock is completed, it is packed and crowned by the driven roller 79, and the knife 91 severs the 80 crown-forming stems or stalks of the grain, so that the crown may be better shaped and will have less liability to blow off under the action of wind, than it would have if the crown-forming stems or stalks projected. 85

The knife 91 is formed from a plurality of arcuate sections 92 whose ends overlap each other and are provided with lugs 93 fitting between corrugations 94 of the roller 79. Anchoring bolts 95 which lie between 90 the corrugations 94, pass through openings in the lugs 93 and are engaged with appropriate ears or the like 96 on one end of the roller 79. This roller is longitudinally tapered and it will be observed that the anchoring bolts 95 draw the annular knife 91 toward the large end of said roller, so that said knife is tightly wedged into place.

While the general operation of the machine would probably be understood from the foregoing, it may be briefly described as follows. The machine is connected abreast of and advances with a harvesting machine (not shown). With the frame D raised as in Fig. 1 and the receiver R in its foremost position as seen in said view, and with the table 32 rotating, the harvester discharges the cut grain into the receiver and thus a shock is gradually formed in the latter. When the shock has reached a sufficient height, it is 100 105 110

finished off by the crowning roller 79, cutting off the stems or stalks of the grain by the knife 91, facilitating the finishing operation as above explained. When the shock is finished, the operator releases the latch means 25, whereupon the drop frame D and the loaded receiver R, immediately move downwardly and rearwardly. About simultaneously with releasing the latch means 25, the operator throws in the clutch 74 and 115 throws out the clutch 51. Thus, while rotation of the table 32 is stopped, the chains 64 are driven, causing the links 75 to rearwardly slide the receiver R, thereby pushing the completed shock from the table. The gate section 61 clears the shock in the manner above explained. The shock having been discharged, the chains 64 and links 75 function to forwardly move the receiver R to the limit allowed by the stops 78, and when this 120 125 130

limit has been reached, the receiver forwardly pushes against the drop frame D, thereby causing upward swinging of the hangers 20 and the cranked axle 12 and again raising the frame D to its normal position.

5 When it reaches this position, it is held by the latch means 25 and the machine is then in readiness for the formation of another shock.

10 While excellent results may be obtained from the general relation of elements herein disclosed, I wish it understood that the present showing is for illustrative purposes only and that within the scope of the invention as claimed, numerous variations and refinements may be made.

20 In Fig. 5, a modified structure is shown in which the major central portion 12^a of the cranked axle is formed by a channel bar, cranked axle ends 12^b being connected with the ends of said bar by suitable bearings 12^c. 12^a denotes a reinforcement around the vertical portion of the axle end 12^b which may be cast in place. 13^b denotes a bearing corresponding to the bearing 13, and it will of course be understood that one of the axle ends 12^b is engaged with the bull wheel W and the other with the wheels W'.

I claim:—

30 1. In a grain shocker of the type embodying a shock-supporting table, a rearwardly shiftable shock-forming receiver over said table, and means for rearwardly shifting said receiver to push a shock from the table; a drop frame carrying said table, a main frame having ground wheels, means mounting said drop frame on said main frame for vertical movement with respect to the latter, and means for holding said drop frame raised until a shock is to be pushed from said table.

35 2. In a grain shocker of the type embodying a shock-supporting table, a rearwardly shiftable shock-forming receiver over said table, and means for rearwardly shifting said receiver to push a shock from the table; a drop frame carrying said table and said receiver, a main frame having ground wheels, means mounting said drop frame on said main frame for vertical movement with respect to the latter, and means for holding said drop frame raised until a shock is to be pushed from said table.

40 3. In a grain shocker of the type embodying a shock-supporting table, a rearwardly shiftable shock-forming receiver over said table, vertical side frames at opposite sides of said receiver having tracks upon which said receiver is mounted, and means for rearwardly shifting said receiver to push a shock from the table; a drop frame upon which said side frames and said table are mounted, a main frame having ground wheels, means mounting said drop frame on said main frame for vertical movement with respect to the latter, and means for holding said drop frame raised

until a shock is to be pushed from said table.

4. In a grain shocker of the type embodying a shock-supporting table, a rearwardly shiftable shock-forming receiver over said table, and means for rearwardly shifting said receiver to push a shock from the table; a drop frame carrying said table, a main frame having ground wheels, front and rear swingable hangers connecting said drop frame with said main frame and allowing vertical movement of the drop frame, and means for holding said drop frame raised until a shock is to be pushed from said table.

5. In a grain shocker of the type embodying a shock-supporting table, a rearwardly shiftable shock-forming receiver over said table, and means for rearwardly shifting said receiver to push a shock from the table; a drop frame carrying said table, a main frame having ground wheels, a rear cranked axle and a front pivoted hanger connecting said drop frame with said main frame and allowing vertical movement of the drop frame, and means for holding said drop frame raised until a shock is to be pushed from said table.

6. A grain shocker comprising a main wheeled frame, a drop frame movable from a normal raised position to a lowered shock-discharge position, a shock-supporting table mounted on said drop frame, a shock-forming receiver and means mounting it shiftable on said drop frame for movement from a normal forward position over said table to a rear shock-discharging position, releasable means for holding said drop frame in said normal raised position while forming a shock and for allowing lowering of said drop frame to said shock-discharge position when released, and means for shifting said receiver first rearwardly and then forwardly upon the lowered drop frame and for raising said drop frame after said forward return of said receiver.

7. A grain shocker comprising a main wheeled frame, a drop frame movable from a normal raised position to a lowered shock-discharge position, a shock supporting table mounted on said drop frame, a shock-forming receiver and means mounting it shiftable on said drop frame for movement from a normal forward position over said table to a rear shock-discharging position, releasable means for holding said drop frame in said normal raised position while forming a shock and for allowing lowering of said drop frame to said shock-discharge position when released, means for shifting said receiver first rearwardly and then forwardly returning it upon the lowered drop frame, and means co-operable with said receiver-shifting means for restoring said drop frame to its normal raised position after said receiver has been forwardly returned upon the lowered drop frame.

8. A grain shocker comprising a main

having corrugations, said knife being formed of arcuate overlapped sections having lugs at their ends fitting between the roller corrugations, anchoring bolts passing through said lugs and lying between said corrugations, and means connecting said bolts with said roller.

In testimony whereof I affix my signature,
CHRISTIAN CHRISTIANSEN.
